(57) **CLAIM**

The ornamental design for a pipe assembly as shown and described.

DESCRIPTION

FIG. 1 is a perspective view of the pipe assembly of the present invention;

FIG. 2 is a front view of the pipe assembly shown in FIG. 1;

FIG. 3 is a rear view of the pipe assembly shown in FIG. 1; FIG. 4 is a left side view of the pipe assembly shown in FIG. 1;

FIG. 5 is a right side view of the pipe assembly shown in FIG. 1;

FIG. 6 is a top view of the pipe assembly shown in FIG. 1; FIG. 7 is a bottom view of the pipe assembly shown in FIG. 1;

FIG. 8 is a perspective view of the pipe assembly with a plug removed from the assembly;

FIG. 9 is a front view of the pipe assembly shown in FIG. 8;

FIG. 10 is a rear view of the pipe assembly shown in FIG. 8;

FIG. 11 is a left side view of the pipe assembly shown in FIG. 8;

FIG. 12 is a right side view of the pipe assembly shown in FIG. 8;

FIG. 13 is a top view of the pipe assembly shown in an alternative configuration of use; and,

FIG. 14 is a bottom view of FIG. 13.
